UNITED STATES PATENT OFFICE.

JOHN L. MCSPADDEN AND JOHN RAILTON, OF DETOUR, MICHIGAN.

STOVEPIPE-DAMPER.

SPECIFICATION forming part of Letters Patent No. 624,073, dated May 2, 1899.

Application filed October 12, 1897. Serial No. 654,997. (No model.)

To all whom it may concern:

Be it known that we, JOHN L. MCSPADDEN and JOHN RAILTON, citizens of the United States, residing at Detour, in the county of 5 Chippewa, State of Michigan, have invented a new and useful Stovepipe-Damper, of which the following is a specification.

The special object of the invention is to make a stovepipe-damper which will prevent 10 soot from entering pipes above the damper, the unnecessary waste of fuel, and the usual escape of heat.

Figure 1 of the drawings is a perspective view giving an interior view when the damper 15 has been closed; and Fig. 2, an elevation showing the damper open, so as to allow a maximum draft.

In the drawings, A A represent two plates, pivoted together at the upper end, of sufficient 20 width to fit snugly across the pipe-chamber B and each provided on the outside with a tube C, open at the lower and closed at the upper end.

c c are holes or openings through the plates 25 and tubes for the inlet of smoke, the draft through them being regulated by a sliding valve D, while E is a wire frame with a suitable handle e, by which the plates A A may be held more or less spread out at the bottom,

so as to form the interior chamber F and the 30 exterior chamber G of the pipe-apartment B.

The smoke enters the interior chamber F, passes up and through holes c into the tubes C, down these tubes and out at the lower end into the chamber G, whence it passes out at 35 the upper end into the discharge-pipe.

The wire frame may be provided with spring and latch to secure it at any desired adjustment between the plates.

Having thus described all that is necessary 40 to a full understanding of our invention, what we claim as new, and desire to protect by Letters Patent, is—

The combination of a pipe, two plates pivoted at their top at or near the center of pipe 45 and adapted to normally hang vertically together in the center thereof, each plate being provided with an opening at or near its top; a tube arranged on each plate having one end communicating with the opening in the plate 50 to which it is attached and the lower end open and means for separating the plates.

JOHN L. MCSPADDEN.

JOHN RAILTON.
